[57] CLAIM

The ornamental design for an oven control panel, as shown and described.

DESCRIPTION

FIG. 1 is a perspective view of an oven control panel showing my ornamental design;

FIG. 2 is a perspective view showing an alternately positioned oven control panel showing my ornamental design;

FIG. 3 is a front view of the oven control panel shown in FIG. 1, which is typical of a straight on view of both FIGS. 1 and 2, showing my ornamental design;

FIG. 4 is a top plan view of the oven control panel shown in FIG. 1 showing my ornamental design;

FIG. 5 is a bottom view of the oven control panel shown in FIG. 1 showing my ornamental design;

FIG. 6 is a right side view of an oven control panel shown in FIG. 1, which forms a typical side view, showing my ornamental design;

FIG. 7 is a perspective view of the oven control panel shown in FIG. 2, with environmental oven structure removed for the sake of clarity, showing my ornamental design;

FIG. 8 is a right side view of the oven control panel shown in FIGS. 2 and 7, which forms a typical side elevation view, showing my ornamental design;

FIG. 9 is a top plan view of the oven control panel shown in FIGS. 2 and 7-8 showing my ornamental design; and,

FIG. 10 is a bottom plan view of the oven control panel shown in FIGS. 2 and 7-9, showing my ornamental design.
